FOLDING TYPE CAN OPENER

William H. Schulz, St. Paul, Minn., and Lois E. Boehm, Milwaukee, Wis., assignors, by mesne assignments, to Western Newell Mfg. Co., Freeport, Ill., a corporation of Illinois

Application October 17, 1949, Serial No. 121,712

2 Claims. (Cl. 30—16)

1

This invention relates to improvements in can openers and refers particularly to openers designed to produce a pouring opening in the end wall of a can as for instance such cans in which beer and other beverages are now commonly sold. An example of the type of can opener to which this invention pertains is found in Patent No. 1,996,550 issued to D. F. Sampson et al.

This type of can opener received its impetus with the advent of canned beer; and breweries now usually enclose one of these openers with each case of canned beer. To guard against the sharp piercing point of the opener puncturing the walls of the corrugated paperboard case, a protective sheath is often placed over the piercing point. But this adds to the cost of the opener and, of course, is a purely temporary expedient.

A more practical solution to the problem is provided by the patent to J. M. Hothersall No. 2,188,352 wherein the desired protection is obtained by "Jack Knifing" the opener upon itself. The present invention follows this patent to the extent that it provides an opener having two sections foldable upon each other, but has as its object to provide a folding type can opener of the character described which may be produced at no greater cost than the conventional one piece can openers represented by the aforesaid Sampson et al. patent.

With this objective in view it is a further and more specific object to provide a novel hinged connection between the punch and handle sections of the opener which is so constructed that within itself it provides the necessary knuckle connection to restrain the sections against relative swinging movement in one direction beyond the point at which they are in substantially end-to-end relationship.

Another object of this invention is to provide a folding can opener of the character described wherein a novel coaction exists between the hinge connection of the opener and the bottle opener with which such openers are equipped to the extent that the hole which results from the formation of the bottle cap remover provides a pocket into which the piercing point is received when the opener is in its folded condition.

Still another object of this invention is to provide a simple detent means for holding the opener in its folded condition.

With the above and other objects in view which will appear as the description proceeds, this invention resides in the novel construction, combination and arrangement of parts substantially as hereinafter described, and more particularly

defined by the appended claims, it being understood that such changes in the precise embodiment of the hereindisclosed invention may be made as come within the scope of the claims.

5 The accompanying drawings illustrate one complete example of the physical embodiment of the invention constructed in accordance with the best modes so far devised for the practical application of the principles thereof, and in

10 which:

Figure 1 is a perspective view of a can opener of the character described shown folded;

Figure 2 is a side elevational view of the opener in its folded condition with a part of the punch section broken away and in section to illustrate the detent action of this form of the invention;

Figure 3 is a side elevational view of the opener in its extended or operative position;

Figure 4 is a perspective view of the hinge connection per se;

Figure 5 is a perspective view illustrating the manner in which the opener is used to produce a pouring opening in an end wall of a can;

Figure 6 is a perspective view illustrating the 25 manner in which the opener is employed to remove bottle caps;

Figure 7 is a perspective view similar to Figure 1 but illustrating a slightly modified embodiment of the invention;

Figure 8 is a detail sectional view taken through Figure 7 on the plane of the line 8—8;

Figure 9 is a side elevation view of the opener shown in Figure 7 but with the punch and handle sections in their operative end-to-end relationship; and

Figure 10 is a developed plan view of the hinged end of the punch section of that form of the invention shown in Figure 7.

Referring now particularly to the accompanying drawings the numerals 5 and 6, respectively, 40 designate the punch and handle sections of the opener. These sections are hingedly connected as at 7 to enable the same to be folded upon each other as shown in Figure 1 or swung into 45 end-to-end relationship as shown in Figure 3.

Both sections are preferably stamped and formed from band stock so that the body of each is substantially a flat bar. The punch section 5 has a piercing point 8 at one end thereof and at its other end has a transverse slot 9 which provides part of the hinge connection. The piercing point 8 is bent and slightly curved out of the general plane of the punch section, and at the base thereof a tongue or prong 10 is struck 55 from the body of the punch section to underlie

the piercing point in such a manner as to provide a fulcrum engageable under the rim 11 of a can as shown in Figure 5.

As is well known with the fulcrum 10 thus hooked under the rim 11 the piercing point 8 overlies the end wall 12 of the can so that as the punch section is rocked upwardly the desired pouring opening will be produced.

The handle section 6 has its outer end bent as at 13 to provide an offset end portion 14. A tang 15 is struck from the bent portion 13 to underlie the offset end portion 14 and coact therewith to form a bottle cap remover which functions in the manner shown in Figure 6.

Attention is directed to the fact that in the formation of the tang 15 a hole or opening 16 is produced.

The hinge connection 7 consists of a loop 17 on the handle section encircling the land 18 left between the slot 9 and the adjacent end of the punch section. The loop is formed from a tongue extended from the end of the handle section and passed through the slot 9 before the loop is fully formed.

Attention is directed to the fact that the tongue is curled back over the top of the handle section. As a result, the two sections can be folded upon each other only in the direction in which the piercing point faces the handle section, and because of the relative dimensions of the two sections the piercing point enters the hole or opening 16 in the handle section. The tang 15 and the nesting of the piercing point in the hole 16 thus coact to provide protection against accidental contact with the piercing point.

Detent means are provided for holding the sections in their folded relationship, and in that embodiment of the invention shown in Figure 1 the detent action results from the specific shape of the hinge loop. Thus, as best shown in Figure 2, the loop has a substantially flat portion 19 spaced from the opposite arcuate portion 20 a distance slightly less than the width of the land 18. As the sections are folded onto each other the inclined flat portion 19 serves as a cam face to wedge the land 18 between it and the opposite arcuate portion 20 to hold the sections in folded condition, the resiliency of the loop making this action possible.

In that embodiment of the invention shown in Figure 7 the detent is provided by opposed protuberances 21 on the side edges of the loop 17, so placed with respect to the circumference of the loop, which in this case is round as shown in Figure 9, that in passing from folded condition to extended condition the protuberances must move from one side to the other of the punch section. By accurately dimensioning of the parts so that the width of the loop across the high points of the protuberances 21 slightly exceeds the length of the slot 9, it will be seen that the protuberances will frictionally hold the opener sections folded upon each other. This action is further assured by the inclined cam surfaces 22 which extend from the tops of the protuberances and form the sides of the end portion of the loop.

In each embodiment of the invention shown, the end of the loop is spaced from the adjacent body of the handle section a distance to receive the land 18 therebetween, such engagement being

permitted by having the slot 9 wide enough to accommodate the necessary endwise shifting of the sections with respect to each other after they have been brought into end-to-end relationship. In this manner the hinge connection may be locked to secure the two sections against relative displacement in either direction and thereby provide a relatively stiff lever for manipulation of the opener in the manner shown in Figure 5.

From the foregoing description taken in connection with the accompanying drawings it will be readily apparent to those skilled in this art that this invention provides a can opener which can be produced at little or no increase in cost over and above that of the conventional one piece opener, and that by virtue of the entry of the piercing point into the protective pocket resulting from the formation of the bottle cap remover a unique protection is afforded against accidental contact with the piercing point.

What we claim as our invention is:

1. A folding can opener for producing a pouring opening in an end wall of a can, comprising: a punch section and a handle section hingedly connected together; a piercing point at the outer end of the punch section; and a fulcrum on the punch section adjacent to the base of the piercing point and underlying the same to hook under the rim of a can bounding the end wall in which a pouring opening is to be produced, with the piercing point over said end wall, the hinge connection between the sections comprising a tongue extended from one of the sections through a slot in the other section, and curled around the land left between the slot and the extreme end of the section in which the slot is formed, said slot being wide enough to accommodate relative endwise shifting of the sections when said sections are in end-to-end relation, and the end of the loop overlying the body of the section from which the tongue extends and said end being spaced a distance from said body to form a recess adapted to receive said land on the end of the other section when it is desired to hold the sections in end-to-end relation for can piercing manipulation of the opener.

2. The folding can opener set forth in claim 1 further characterized by the provision of detent means for yieldingly holding the sections folded upon each other, said detent means comprising protrusions on the opposite side edges of the loop, the sides of said protrusions serving as cams and the height of the protrusions being such that the width of the loop across the tops of the protrusion is slightly in excess of the length of the slot so that as the sections are swung on the hinge connection said protrusions are cammed from one side to the other of the section in which the slot is formed.
